FAY A. BROGDEN, OF SYRACUSE, NEW YORK, ASSIGNOR TO PASS & SEYMOUR, INC., OF SOLVAY, NEW YORK, A CORPORATION OF NEW YORK.

PULL PENDENT SWITCH.

1,156,344.

Specification of Letters Patent. Patented Oct. 12, 1915.

Application filed July 12, 1912. Serial No. 709,043.

To all whom it may concern:

Be it known that I, FAY A. BROGDEN, a citizen of the United States, residing at Syracuse, county of Onondaga, State of New York, have invented certain new and useful Improvements in Pull Pendent Switches, of which the following is a specification.

This invention relates to switches and 10 more particularly to a pull pendent switch.

The invention has for one of its objects to provide a simple, efficient and easily assembled switch and one which may be quickly connected to or disconnected from the circuit 15 which is controlled.

Another object is to construct a device of this character in which the operating mechanism may be easily accessible for adjustment and which presents an ornamental appearance.

Other objects and the novel features of the invention will be apparent from the following description taken in connection with the accompanying drawings, in which:

25 Figure 1 is an elevation of the improved switch, one-half of the shell being raised and part of the other half being broken away to expose the switching mechanism on the interior thereof. Fig. 2 is a vertical sectional view of the switch taken along the line 2—2 of Fig. 1 with the shell closed. Fig. 3 is a vertical cross sectional view along the line 2—2 of Fig. 2 showing the operating mechanism, parts thereof being in elevation. Fig. 4 is an elevation of the inner side of one of the insulating blocks upon which the operating mechanism is mounted. Fig. 5 shows views of both sides of the movable contact plate or bridging member. Fig. 6 30 shows views of both sides of the disk for actuating the contact member and to which one end of the pull chain or cord is secured. Fig. 7 shows separated top plan views of the pivot pin and retracting spring mounted 35 thereon. Fig. 8 is an elevation of the inner side of one of the insulating supporting blocks. Fig. 9 is a perspective view of one of the metallic fastings or switch contacts.

Referring to the drawings the switch has 40 an outer inclosing casing or shell of brass or

similar material comprising two halves 10 and 11, each half being lined with fiber or other insulating material. The two halves have their meeting edges threaded as at 12 and 13. The threads 12 engage over the 55 threads 13 on the upper part 11 and lock the two halves together, thus completely inclosing and insulating the switch mechanism on the interior. The lower half 10 has a central opening 14 therein and has a flaring chain or cord guide 15 soldered or otherwise secured to the shell 10. Two openings 16 are provided on the lower face of the section 10 on opposite sides of the chain guide 15 to receive screws 16' by means of which 60 the shell 10 and the insulating supporting body are rigidly connected together. The upper half 11 of the shell has an opening 17 vertically in line with the opening 14 in the lower half. The opening 17 has a bushing 17' secured therein through which the 65 circuit wires 18 and 19 enter the interior of the casing.

Each of the two blocks of insulating material 20 and 21, which comprise the insulating supporting body for the operating mechanism, have a stationary nut 22 set into and rigidly held in holes 23 therein, which holes are plugged up with insulating material. The nuts 22 on the interior of the 75 blocks 20 and 21 are threaded and adapted to receive the ends of the screws 16' which extend through openings 16 in the shell and openings 24 in the blocks 20 and 21. The blocks 20 and 21 are separated a certain 80 distance by the three brass spacing posts 25, 26 and 27 which are channeled-shaped having right-angled sections at their ends forming feet by means of which they are secured to the blocks and terminal plates. The 85 blocks 20 and 21 are segmental in horizontal cross section and nearly rectangular in vertical cross section, being slightly rounded at the corners. The blocks, together with their spacing means thus form a cylinder 90 having a central longitudinal gap therein. The cylinder will conform to and be held securely by the inner cylindrical walls of the inclosing casing. The feet on the opposite 95 ends of the spacing post 25, 26 and 27 are 100

seated in recesses in the opposing faces of the blocks 20 and 21. The post 26 is a conductor and constitutes part of the circuit and at one end is connected to the terminal plate 28, to which the conductor 18 is connected by means of the screw 29. The terminal plate 28 is seated in a recess 30 in the upper end of the insulating block 20. The post 26 conducts the current across the gap between the two insulating blocks 20 and 21 to the foot in engagement with the block 21 which is in electrical contact with the foot 31 of a metallic facing plate 32 curved to seat against the face of an incline 33 on the peripheral face of a reduced portion or boss 34 of the insulating block 21. The boss or reduced section 34 is of insulating material and integral with the block 21 and has three other similar segmental seats or inclines 35, 36 and 37 arranged about its periphery whose faces are perpendicular to the inner face of the block 21. The inclines are arranged symmetrically and the incline 36 opposite the incline 33 also has a metallic facing 38 similar to the face plate on incline 33 shown in Figs. 4 and 9. Each of the inclines has an abrupt shoulder 39, whereby a quick make and break of the circuits is obtained.

30 The conductor 19 is connected to the terminal plate 40 by means of the terminal screw 41. The terminal plate 40 and screw 41 are seated in a recess 42 at the upper end of the insulating block 21 and are connected to the foot of the spacing post 25 in engagement with the block 21 by means of the through screw 43. The foot of the facing plate 38 is in electrical contact with the foot of the spacing post 25. It will thus be seen that current is at all times connected to the facing plates 32 and 38 and in order to close the circuit I provide the bridging member or movable contact plate shown in Fig. 5. The bridging member comprises a plate 44 stamped from a single sheet of conducting metal and provided with the four recesses 45. At its outer end the contact plate has secured thereto the diametrically oppositely facing spring contact fingers 46 and 47. One end of each of the contact fingers 46 and 47 is riveted or otherwise secured to the end of the plate 44 and the other end is bent upon itself to form a resilient contact device to spring over the inclines on the reduced section 34 of the insulating block 21. When the contact fingers 46 and 47 are in engagement with the face plates 32 and 38 the circuit will be completed and when in engagement with the non-conducting seats or inclines 35 and 37 the circuit will be broken.

The bridging plate 44 has a central circular opening 48 therein which is adapted to receive the shank 49 of the pivot pin 50 and

be loosely mounted thereon. To operate the plate 44 and alternately make and break the circuit I have provided the wheel shown in Fig. 6. The said wheel comprises a segmental sheet of fiber 51 which has a central aperture 52 over which a plate 53 is fitted. The plate 53 is stamped from sheet metal and has two lugs 54 thereon which are forced through the fiber and clenched on the opposite side to secure the sheet 53 to the member 51. The plate 53 is also provided with a central aperture 55 and has a hub 75 portion 56 by means of which the operating wheel is loosely pivoted on the shank 49 of the pivot pin. Teeth 57 are punched up from the periphery of the plate 53 corresponding to the recesses 45 in the bridging member 44 to engage in the recesses 45 and operate the said bridging member as is usual. A tongue 58 is punched down from the face of the plate 53 and is disposed within the opening 52 for a purpose to be described. On the periphery of the fiber segment 51 there is a chain guide or carrier 59 adapted to receive the inner end of the cord or pull chain 60 which passes through the opening 14 and depends centrally from the switch casing. The chain or cord carrier 59 has a bent and slotted tongue 61 at its upper end to receive the end ball on the chain or cord 60 and holds the same from working loose within the casing but is arranged so that the chain may be removed therefrom. The blank forming the chain guide 59 has lugs 62 formed therewith which may be forced through the fiber member 51 or holes therein and clenched on the opposite side to fasten the chain guide to the said fiber member. The bridging member shown in Fig. 5 is loosely mounted on the pivot pin 49 and bears on one side against the face of the reduced portion 34 on the insulating block 21. The contact fingers 46 and 47 on said bridging member fit onto the periphery and ride over the inclines on said reduced section 34. The operating member shown in Fig. 6 fits against the other face of the bridging member and the teeth 57 on the operating member are arranged to engage the recesses 45 in the bridging member. To hold the operating member in engagement with the bridging member there is a torsion spring 63 which encircles the pivot pin 49 and one end 64 thereof locks under and bears against the tongue 58 on the plate 53 and the other end 65 passes through a hole 66 in the angular head 67 of the pivot pin 50. The head 67 fits into a socket 68 in the insulating block 20. The socket 68 has an angular portion 69 which keeps the pivot pin from turning when the angular head 67 is seated therein. A shank 49 of the pivot pin fits into and seats against a spiral spring 70 arranged in

a central socket 71 in the inner face of the insulating block 21. The spring 70 and the shank 49 are about the same external diameter and of a diameter equal to the inner 5 diameter of the socket 70. The head 67 of the pivot pin is provided with a slot 72 and has the corners cut away. An opening 73 extends into the socket opening 68 so that a screw driver may be inserted and engage 10 the slot 72 on the head of the pivot pin to force the same inwardly and turn the pivot pin for the purpose of adjusting the tension of the spring 63. The pivot pin may be freely rotated when forced inwardly against 15 the pressure of spring 70 and which latter will force the pin back into the angular socket 69 when the desired adjustment of the retracting spring 63 has been effected.

The operation of the device will be briefly 20 stated.

The leading in wires 18 and 19 of the circuit to be controlled having been connected to the terminal plates 28 and 40 and the two halves of the casing or shell having been 25 connected together the switch is in condition to be operated by successively pulling the chain or cord 60, thus alternately making and breaking the circuit. The chain 60 will 30 actuate the fiber segment 51 which has the toothed plate 53 secured thereto. A pull on the chain 60 will step the bridging member 44 around a quarter of a turn, moving the contact fingers 46 and 47 from the incline upon which they are bearing to the next succeeding incline. In the position shown in Fig. 2 the circuit is made, the contact fingers bearing on the inclines provided with the facing plates 32 and 38. A pull on the cord or chain 60 will break the circuit and the operating segment 51 will be retracted by 35 the spring 53 so that the teeth 57 will engage in succeeding recesses 45 on the bridging member. As shown in Fig. 2 the spacing post 25 constitutes a stop for the fiber segment 51 which engages against the lower edge of said post 25 when the segment is in its retracted position. The spacing post 27 co-operates with the chain slot or holder 59 to guide the chain 60, and maintain the same 40 in its proper path, the chain bearing along the inner face of the post 27 as is indicated in Fig. 2.

It will be seen that I have constructed a simple and inexpensive switch for the purposes set forth and as various modifications may be made in the details without departing from the spirit of the invention I do not wish to be limited to the exact details as shown and described.

Having thus described the invention what is claimed as new is:

1. In a switch the combination of a supporting body of insulating material, suitable

terminals on one end thereof, switching mechanism mounted on the body, operating 65 means for said switching mechanism, and a casing inclosing said body and comprising two detachably connected parts, each inclosing a portion only of the insulating body, one of said parts being rigidly secured 70 to the insulating body so as to leave the upper portion of the body and said terminals exposed when the other part of the casing is removed, whereby access may be had to the terminals without disconnecting 75 one part of the casing from the insulating body.

2. In an electric appliance the combination of a supporting body comprising insulating material, suitable terminals on the 80 side of said body near one end thereof, a casing for said body comprising two detachably connected parts, one of said parts being of such size as to inclose only a portion of 85 said body, leaving exposed the side thereof near said terminals, and means for attaching said one part of the casing to the insulating body, the construction and arrangement being such that access may be had to said terminals without detaching said one part of 90 the casing from the insulating body.

3. In a switch, the combination of a supporting body of insulating material comprising two sections spaced apart, suitable terminals on said body, switching mechanism supported on said body between said sections, and adapted to electrically connect 95 said terminals, a casing completely inclosing said body and comprising two detachably connected parts, a threaded member embedded in each section of the insulating body, and screws accessible from the exterior of the casing and engaging one of the parts of the casing and said threaded member in each of said sections of the insulating body 100 whereby said sections and one part of the casing are all rigidly connected together.

4. In an electric switch the combination of a supporting body comprising two spaced blocks of insulating material, one of said blocks having a reduced section or boss with inclines arranged on the peripheral face thereof and extending into the space between said blocks, switch contacts on alternate inclines, a conducting plate rotatably mounted 110 on an axis concentric with the boss and having resilient contact fingers disposed at right angles thereto and engaging the inclines on the boss, and means for rotating said plate to make and break the circuit.

5. In an electric switch the combination of a supporting body of insulating material, a pivot pin mounted thereon, contacts on said body, and a switch member for successively connecting and disconnecting said 125 contacts, said switch member comprising a

flat plate of conducting material having a central opening to fit said pivot pin, spring fingers having ends secured to the ends of the plate at opposite sides of the center and having their broad faces disposed at right angles to the broad face of said plate, the free ends of the fingers being reversely disposed with respect to the secured ends, curving about the pivotal axis of the plate and

tending to spring inwardly toward the center of the plate and into contact with said contacts.

In testimony whereof I affix my signature in presence of two witnesses.

FAY A. BROGDEN.
